F. MANKEY.

MOLDING.

No. 17,134.

Patented Feb. 22, 1887.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 17,134, dated February 22, 1887.

Application filed July 1, 1886. Serial No. 206,869. Term of patent 7 years.

To all whom it may concern:

Be it known that I, FREDERICK MANKEY, of Williamsport, Lycoming county, Pennsylvania, have invented and produced a new and original Design for Ornamental Trims or Moldings, of which the following is a specification, reference being had to the accompanying photograph, forming part hereof.

My design relates to an ornamental trim or molding in the form of a band or bar; and it consists in the configuration thereof, substantially as represented. On each edge of the band appears a series of scallops or convexities, A, a portion, as B, of each convexity being steeper or less inclined than the remaining portion, C. Upon the face of the band are circular depressions D. Extending from said

depressions are channels or scores E, which meet the points of junction of the convexities A on opposite sides of the bar or band. 20

The general appearance of my design is that of a series of heart-shaped figures repeated in regular order, as shown.

I claim—

The design for an ornamental trim or molding, which consists in the irregular scallops A on opposite edges of the bar and the scores E and recesses D on the face of said bar, substantially as herein shown and described. 25

FREDERICK MANKEY.
